CONDIMENT DISPENSER

William H. Youngerman, Chicago, Ill., assignor to Merchants Sales Corp., Chicago, Ill., a corporation of Illinois

Application January 13, 1951, Serial No. 13,784

Term of patent 3½ years

(Cl. D44—22)

To all whom it may concern:

Be it known that I, William H. Youngerman, a citizen of the United States, residing at Chicago, State of Illinois, have invented a new, original, and ornamental Design for Condiment Dispenser, of which the following is a specification, reference being had to the accompanying drawing, forming a part hereof.

Fig. 1 is a perspective view of a condiment dispenser, embodying my new design;

Fig. 2 is a side view;

Fig. 3 is a top plan view; and

Fig. 4 is a bottom plan view thereof.

I claim:

The ornamental design for a condiment dispenser, substantially as shown.

WILLIAM H. YOUNGERMAN.
